UNITED STATES PATENT OFFICE.

IGNATIUS RANCADORE AND LEOPOLD PECORARO, OF SAN JOSE, CALIFORNIA.

CANNING DEVICE.

Application filed April 26, 1922. Serial No. 556,795.

To all whom it may concern:

Be it known that we, IGNATIUS RANCADORE, a citizen of the United States, and LEOPOLD PECORARO, a subject of the King of Italy, and residents of San Jose, county of Santa Clara and State of California, have invented a new and useful Canning Device, of which the following is a specification.

The present invention relates in general to the canning industry and has reference more particularly to a device facilitating the canning or packing of food products, such as vegetables, especially string beans, asparagus or the like, which for the purpose of convenience in canning as well as to offer an appetizing commodity, are usually packed in a can in upstanding position with the pieces arranged substantially parallel to one another.

20 The primary object of the invention is to provide a device for packing such a commodity as above mentioned in the can in a convenient and practicable manner without mutilating the same or otherwise taking 25 away from its attractive appearance when the can is opened for use.

A further object of the invention is to produce a device which may be cheaply manufactured and conveniently used and offering 30 a means whereby the commodity may be packed in the can without requiring an unusual amount of skill on the part of the operator.

The invention possesses other features 35 which will clearly appear as the description now proceeds with reference to the illustrative embodiment of the device as shown in the accompanying drawing in which Figure 1 is a view in end elevation of the device; Figure 2 is a similar view showing the handle and the plate carried thereby as elevated; Figure 3 is a view in side elevation of the device and Figure 4 is a view in side elevation of the device as placed over a can for transferring the commodity from the 45 device to the can.

Referring now to the drawing in detail the device in its preferred form comprises a cylinder (1) formed of relatively light sheet metal of the desired length and having a diameter of substantially that of a can into which the commodity to be canned is transferred from the device as will hereinafter appear.

50 The cylinder (1) more specifically embodies an open sided structure with the open-

ing therein as best shown in Figure 2, extending the length of the cylinder. Projected at an obtuse angle to the cylinder on one side thereof is a forked bracket or the like (2), the forks thereof, which are two in number, being arranged parallel and made to receive between them one end of a handle or lever (3) with an opening in the end of the handle made to register with openings in the two forks of the bracket so that a screw, bolt, rivet, or the like (4) may be passed through the registering opening to pivotally connect the handle to the bracket, leaving the same free to be pivotally moved relatively thereto. The handle is arranged transversely of the cylinder and adapted to be moved radially thereof and providing a suitable mounting and manipulating member for a plate (6) which is curved to correspond to the curvature of the circumference of the cylinder and with the plate further made of a dimension to occupy the opening in the side of the cylinder as best shown in Figure 1. The longitudinal edges of the plate (6) as well as the edges of the opening in the cylinder are bevelled to make a positive fit between the plate and the openings in the cylinder. Extending along the sides of the opening in the cylinder are curved guide plates (7) and (8). Each of the plates are slotted as at (9), to receive the handle (3) in order to align the plate (6) with the opening in the cylinder. The curved guide plates (7) and (8) are curved to correspond to the path of the plate as best shown in Figure 2 when the plate is moved to and from the opening in the cylinder, in fact the bevelled edges of the plate have a slight wiping contact with the inside surface of both plates (7) and (8) so as to prevent any particle of the commodity being crushed between the inside surface of the plates (7) and (8) and the edges of the plate (6).

55 The handle (3) is extended and preferably bent to provide a convenient hand grip so that the operator may manipulate the device without difficulty.

Considering the device to be used for packing or canning string beans, the beans are placed in the device through the opening in the side of the cylinder when the plate (6) is raised and the beans arranged in parallel relation to one another, a sufficient 105 number of them placed in the cylinder, whereupon the handle (3) is clasped by the

hand of the operator and brought down so that the plate (6) will impart a pressure to the beans to pack them in the cylinder. A knife is then used to cut the beans protruding beyond the open ends of the cylinder and the operator then places the device over the open end of a can (A). The diameter of the cylinder may be of substantially the diameter of the can but preferably slightly less so that the end of the cylinder telescopes with the open end of the can with the telescoping action limited by the bands (10) and (11) adjacent opposite ends of the cylinder and acting as abutments. It makes no difference which end of the cylinder is placed over the open end of the can. When the cylinder has been placed over the open end of the can as shown in Figure 4 and as just described, a jarring action imposed on the can by lifting it up and dropping it down on the table or the like will transfer the beans from the cylinder into the can, whereupon the ordinary lid may be placed over

the can and the beans thus packed therein. The device may then be used for repeating 25 the operation.

We claim:

A device of the class described comprising an open ended cylinder; said cylinder also having an opening in its side and adapted to receive a commodity to be canned, a lever pivoted transversely of the cylinder, and a curved plate carried by the handle adapted to occupy the space in the open side of the cylinder, the curve of said plate corresponding to the curvature of the cylinder to complete the circumference thereof and curved guide plates along the sides of the opening in the cylinder having slots to receive the handle which carries the plate to 40 align the plate with the opening in the cylinder, said guide plates being curved to correspond to the path of the plate when moved to and from the opening in the cylinder.

IGNATIUS RANCADORE,
LEOPOLD PECORARO.
